Attorney

UNITED STATES PATENT OFFICE

WILLIAM S. BRYAN, OF RICHMOND, VIRGINIA

DOOR-Straightening Tool

Application filed November 4, 1929. Serial No. 404,757.

This invention relates to door straightening tools and more particularly to tools of this character which are especially adapted for use in straightening the doors of automobiles but it is to be understood that a tool constructed in accordance with this invention may be utilized in any manner for which it is found adapted.

An important object of the invention is to provide, in a manner as hereinafter set forth, a door straightening tool of the aforementioned character which is adapted to be expeditiously adjusted to permit the use of the same on doors of different lengths.

Another very important object of the invention is to provide a tool of the aforementioned character wherein the pressure screw which is mounted thereon may be adjusted longitudinally on the supporting beam or bar in a manner to apply pressure to the door upon which the device is mounted at various points within the longitudinal length thereof.

Other objects of the invention are to provide a door straightening tool of the character set forth which will be simple in construction, strong, durable, efficient in its use and which may be manufactured at low cost.

Other objects and advantages of the invention will become apparent from a study of the following specification, taken in connection with the accompanying drawing wherein like characters of reference designate corresponding parts throughout the several views, and wherein:

Figure 1 is a side elevation of a door straightening tool constructed in accordance with this invention showing the same mounted in position on a door, the latter being shown in dotted lines.

Figure 2 is a fragmentary view in front elevation thereof.

Figure 3 is an enlarged horizontal sectional view taken substantially on the line 3—3 of Figure 1, and looking in the direction of the arrow.

Figure 4 is an enlarged detail view in front elevation of the longitudinally adjustable door engaging hook which is mounted on the lower end of the tool.

Referring to the drawings in detail, the

reference character 1 designates an elongated bar or beam which is longitudinally split intermediate its end to provide the spaced parallel side portion 2 which provides the elongated longitudinal slot 3 in said beam. 55 The upper portion of the beam 1 is twisted at right angles, as at 4, and is provided with a horizontally disposed forwardly directed shank or extension 5 which terminates in a down-turned door engaging hook portion 6 which engages over the upper portion of the door, shown in dotted lines in the drawings and designated by the reference character 7. The inner face of the hook 6, at its upper end, 60 is beveled as at 8 and secured to the inner face of said hook through the medium of the securing elements 9, is a pad 10 which extends below the hook 6 and has its lower portion extending forwardly at an obtuse angle. 65

A door engaging hook 11 is mounted for vertical longitudinal adjustment on the beam 1 through the medium of the slotted shank or arm 12 through which said beam extends. The arm 12 fits somewhat loosely about the beam 1 and is held in adjusted position thereon by frictional engagement therewith when pressure is applied to the hook 11 as will be apparent. A stop bolt 13 extends transversely through the lower end portion of the beam 1 for preventing removal of the hook 11 therefrom. The free end of the hook 11 is turned outwardly as at 14 and secured to the inner face thereof through the medium of the securing element 16, is the cushioning pad 17 having the forwardly turned upper end portion illustrated in Figure 1 of the drawing. 70

A rectangular collar 18 encircles the split portion 2 of the beam 1 and is mounted for longitudinal movement thereon. The forward side of the collar 18 is provided with an inwardly extending neck 19 which extends into the slot 3 and said neck and the adjacent portion of the collar are provided with aligned internally threaded bores for threaded engagement with a pressure screw 20 which extends through said slot 3 and projects through an opening 21 in the opposite side of the collar 18. Said opening 21 is of greater diameter than the pressure screw. 75 80 85 90 95 100

At its forward end, the pressure screw 20 has swivelled thereon a work engaging head 22 and the opposite end of the pressure screw is provided with an actuating crank 23.

In the use of the tool, the upper hook is engaged over the upper end of the door and the lower hook is adjusted longitudinally on the beam 1 and engaged under the lower end of the door. The pressure screw 20 is then adjusted to the desired point on the beam through the medium of the slideable collar 18 and is then screwed forwardly into engagement with the door with the obvious result that the intermediate portion of the door will be forced forwardly and the opposite end thereof will be held stationary or drawn rearwardly, as will be apparent. The cushioning pads on the door engaging hook will prevent marring or damaging of the door. The adjustability of the pressure screw 20 permits the application of pressure of different points on the door without the necessity of removing the tool therefrom.

It is believed that the many advantages of a straightening tool constructed in accordance with this invention will be readily understood, and although the preferred embodiment of the invention is as illustrated and described, it is to be understood that changes in the details of construction may be had which will fall within the scope of the invention as claimed.

What is claimed is:—

1. A door straightening tool of the character described comprising an elongated beam having a split intermediate portion providing an elongated longitudinal slot, a rectangular collar encircling the split portion and adapted for longitudinal movement thereover, a door engaging pressure screw threaded through the collar and extending through the slot and adapted to travel longitudinally therein, an actuating crank on one end of the pressure screw, a forwardly and inwardly extending door engaging hook integrally formed on one end of the beam, a forwardly and inwardly extending door engaging hook slidably mounted for longitudinal adjustment on the opposite end portion of the beam and a stop element mounted on the beam adjacent the lower end thereof for retaining the last named hook thereon.

2. A door straightening tool of the character described comprising an elongated beam having a split intermediate portion providing an elongated longitudinally extending slot, a rectangular collar encircling the split portion of the beam and adapted for longitudinal movement thereon, a threaded opening in the forward side of the collar, an internally threaded neck mounted on the inner wall of the collar communicating with the threaded opening and extending into the slot, an unthreaded opening in the opposite side of the collar and aligned with the threaded

opening in the neck and in the opposite side of the collar, a pressure screw extending through the unthreaded opening and threaded through the neck and the threaded opening, a door engaging head swivelly mounted on the forward end of the pressure screw, an actuating crank on the opposite end of the pressure screw, said pressure screw adapted to travel longitudinally through the slot in the beam, an integral door engaging hook extending forwardly and inwardly from the upper end of the beam, a forwardly and inwardly extending door engaging hook slidably mounted for longitudinal adjustment on the lower portion of the beam, means for retaining the last named hook on the beam, and cushioning pads mounted on the inturned portions of the hooks.

In testimony whereof I affix my signature.

WILLIAM S. BRYAN.
